UNITED STATES PATENT OFFICE

GEORGE J. LAMKE, OF BRONAUGH, MISSOURI

NOSE PUNCH

Application filed March 28, 1930. Serial No. 439,667.

This invention relates to new and useful improvements in nose punches of the type adapted for use in forming a hole in the nose of live stock for the insertion of a ring.

5 The primary object of the invention is to provide, in a manner as hereinafter set forth, a manually operable tool of the aforementioned character embodying a construction and arrangement of parts whereby the operation of cutting or punching the hole through the animal's nose may be expeditiously and positively accomplished.

10 The foregoing and still further objects and advantages of the invention may become apparent from a study of the following specification, taken in connection with the accompanying drawings wherein like characters of reference designate corresponding parts throughout the several views, and wherein:—

15 Figure 1 is a view in elevation of a nose punch constructed in accordance with this invention.

Figure 2 is a fragmentary view in front elevation showing the co-acting die and head.

20 Figure 3 is a fragmentary view in section taken substantially on the line 3—3 of Figure 2.

25 Referring to the drawings in detail and to Figure 1 thereof in particular, it will be seen that the reference numerals 1 and 2 designate a pair of handle levers which cross each other and are pivotally connected together as at 3. At their forward ends, the levers 1 and 2 merge into the outwardly, forwardly and inwardly curved arms 4 and 5, respectively.

30 The free end of the arm 4 terminates in an integral enlargement 6 having a tapered free end portion 7 and a bore 8 extending from its forward end and terminating in an intermediate portion thereof on the forward side of said enlargement. The free end of the enlargement 6 is formed to provide a cutting edge 10 adapted for engagement with the free end of a tapered head 11 formed integrally on the free end of the arm 5. The head 11 is preferably of soft material as compared with the enlargement 6 to prevent dulling of the knife edge 10 when the same is engaged therewith.

35 As will be obvious, the device is inserted

in the nostrils of the animal and properly positioned after which the levers 1 and 2 are swung together and the hole is formed in the animal's nose in an obvious manner. The punchings may be expeditiously removed 55 from the bore 8 by inserting a suitable implement thereinto from either end of the same.

It is believed that the many advantages of a nose punch constructed in accordance 60 with this invention will be readily understood, and although the preferred embodiment of the invention is as illustrated and described, it is to be understood that changes in the details of construction may be had 65 which will fall within the scope of the invention as claimed.

What is claimed is:—

A nose punch of the character described comprising a pair of handles, pivotally connected together at one end, outwardly, forwardly and then inwardly curved arms formed integrally on the pivoted ends of the handles, a conical head formed integrally with the free end of one of the arms, a conical head formed integrally with the free end of the other arm having a reversely tapered free end portion terminating in an annular cutting edge engageable with the free end of the first named head, the second named head having an angular bore therein for the passage of slugs extending from the cutting edge to one side of said second named head adjacent the reversely tapered end portion thereof. 75 80 85

In testimony whereof I affix my signature.

GEORGE J. LAMKE.
